WELL TOOLS

John V. Fredd, Dallas, Tex., assignor, by mesne assignments, to Otis Engineering Corporation, Dallas, Tex., a corporation of Delaware

Filed Apr. 16, 1956, Ser. No. 578,498
43 Claims. (Cl. 166—46)

This invention relates to well tools and methods of completing and working over wells, and more particularly to well tools for multiple zone producing wells and methods of completing and working over multiple zone producing wells.

In wells producing from two or more zones, it is desirable to be able to work over each of the zones without pulling the flow conductor or well tubing string from the bore of the well each time the servicing or work-over operations are performed. Many wells are now being completed with parallel strings of tubing or flow conductor for conducting the fluids from each of the zones to the surface. In the conventional installation of dual strings of well tubing or flow conductor, the tube which communicates with the lower zone extends upward from the lower packer through the level of the upper zone or zones and through the upper packer or packers to the surface. Such an installation presents many problems and dangers, such as the danger of perforating the tubing at the time the casing is perforated in the upper zone; or the danger of collapsing the second tubing string during a squeeze cementing or formation fracturing operation. There is also the danger of the possibility of cementing the tubing string to the lower zone and the lower packer in the well permanently when conventional cementing techniques are used.

It is therefore an object of this invention to provide a means and method providing for completing, performing various production operations, working over and producing wells having a plurality of producing zones therein without the necessity of removing the entire string of well tubing or flow conductor from the well.

An object of the invention is to provide a new and improved method of completing multiple zone producing wells.

Another object is to provide a new and improved method of working over, separately, the individual zones of a multiple zone producing well.

Still another object is to provide a new and improved method of working over a well producing from two zones having two tubing strings for conducting flow from the two zones to the surface without pulling either tubing string from the well.

A further object is to provide a new and improved method of working over a well producing from two zones having two tubing strings for conducting flow from the two zones, which permits both the upper zone and the lower zone to be each selectively and individually worked over without pulling of either tubing string from the well.

Another object is to provide a new and improved well apparatus for completing and working over wells producing from a plurality of zones.

Still another object is to provide a new and improved plural housing or nipple having means selectively receiving a plurality of well tools.

A further object is to provide a housing or nipple, of the type described, having a plurality of passages in which

2

different well tools may be received and seated for completing or working over wells.

A still further object of the invention is to provide a new and improved housing or nipple, of the type described, having guide means for selectively guiding each tool to its designated passage.

Another object is to provide a housing or nipple, of the type described, having a plurality of passages of different diameters and having guide means for guiding well tools of different diameters to the passage of proper diameter.

Additional objects and advantages of the invention will be readily apparent from the reading of the following description of a device constructed in accordance with the invention, and reference to the accompanying drawings thereof, wherein:

FIGURE 1 is a schematic sectional view of a well before completion showing the housing or nipple in position in the well casing between two producing zones of the well;

FIGURE 2 is a similar view showing the well completed and producing from both wells;

FIGURE 3 is a similar view showing the manner of work-over of the lower producing zone;

FIGURE 4 is a similar view showing the manner of work-over of the upper producing zone;

FIGURE 5 is a vertical sectional view of the upper part of a twin housing or nipple showing a plug choke in one passage thereof and an extension hanger in the other passage;

FIGURE 6 is a continuation of FIGURE 5 showing the lower portion of the twin nipple;

FIGURE 7 is a fragmentary vertical sectional view of the upper end portion of a housing or nipple having three passages and showing the different sizes of well tools received in each passage;

FIGURE 8 is a top view of the three passage nipple of FIGURE 7 showing the guide ramps for guiding tools to their proper passages;

FIGURE 9 is a top view of a modified form of three passage nipple;

FIGURE 10 is a top view of still another form of three passage nipple; and,

FIGURE 11 is a top view of a four passage nipple.

Referring now particularly to FIGURES 1 through 4 of the drawings, which illustrate schematically the method of the invention for completing and working over wells which have two or more producing zones, the method there illustrated includes disposing a twin housing or nipple 20 in a well casing 21 between two producing zones 22 and 23 of the well, and below the lower ends of two strings 24 and 25 of tubing employed to conduct fluid to the surface from the two producing zones 22 and 23, respectively. The twin nipple or housing member is formed with two passages 28 and 29 which are provided with means, in the form of landing and locking recesses 30 and 31, respectively, for receiving or holding well tools in the passages, whereby well tools may be selectively seated in the two passages, the twin nipple having an internal ramp 33 which guides the well tools to the proper passages, as will hereinafter be described in greater detail. The two tubing strings 24 and 25 also are provided near their lower ends with landing and locking recesses 34 and 35, respectively, whereby tools may be selectively positioned in the tubing strings.

The tubing strings 24 and 25 have a packer or sealing

means 37 which may be any suitable type; for example, that shown in FIGURE 4 of the patent to Hardison, 171,563, to seal between said tubing strings and the casing 21 and the twin nipple is similarly provided with a packer or sealing means 38 which may also be any suitable type, such as that shown in the Baker Oil Tools, Inc. catalogue for Baker Model "DA" Retainer Production Packer, to seal between said nipple and the casing. The tubing string 24 is provided with side ports 39 which serve as by-pass ports for fluids which may be in the well when the upper packer 37 is being lowered into position to facilitate such placement and when said packer is being removed from sealing position, said ports being also useful for other well operations.

To complete the well for production from both zones after the twin nipple or housing member 20 is disposed in the well between the two producing zones, an extension tube 40 is lowered into position in the tubing string 25 to connect between the tubing string 25 and the passage 29 of the twin nipple, whereby well fluid from the lower producing zone 23 may flow to the surface upwardly through the passage 29, the extension tube 40 and the tubing string 25. The extension tube 40 is positioned and locked in position by means of an extension hanger 41 secured to its upper end, and which engages in the landing recess 35. The extension hanger and the extension tube are provided with packers or sealing means 42 and 43, respectively, which seal between the extension hanger and the tubing string 25 and between the lower end of the extension tube and the internal wall of the passage 29 of the twin nipple.

The ramp 33 directs the lower end of the extension tube into the passage 29, as will be hereinafter more fully explained.

A plug choke 44 is then lowered through the tubing string 24 and into the passage 28, where packer or sealing means 45 carried by the choke engages the bore wall of said passage 28 to close such passage and prevent flow of fluid between the two producing zones. The plug choke is directed into the passage 28 by the ramp 33, and is positioned and held in position by locking means which engage in the locking recess 30.

Finally, a side door choke 46 is positioned in the tubing string 24 at the landing recess 34 where it prevents flow of fluids through the side ports 39, said side door choke being provided with longitudinally spaced packers or sealing means 47 and 48 which seal between the choke and the tubing string above and below the side ports.

Well fluid from the upper producing zone 22 then flows into the casing 21 through apertures or perforations 49 in the casing and upwardly to the surface through the longitudinal passage 50 of the side door choke 46 and through the tubing string 24, its flow being controlled by the valve 51 in the tubing head 52 forming a part of the surface connections of the well.

Well fluid from the lower producing zone 23 flows into the casing 21 through the apertures or perforations 53 in the casing below the twin nipple and flows upwardly to the surface through the extension tube 40 and the tubing string 25, its flow being controlled by the valve 54 in the tubing head 52.

When it is desired to work over the lower producing zone 23 by circulating chemicals or other fluids from the surface into the casing 21 below the twin nipple 20 and then back to the surface, the extension tube 40 is removed and replaced by a longer extension tube 60 which extends through the passage 29 and terminates at a point well below the twin nipple 20, as shown in FIGURE 3. The extension tube 60 is positioned and held by means of an extension hanger 61 of the same type as the extension hanger 41. The extension tube 60 is provided with sealing means 62 which seals between the inner wall of the passage 29 and the exterior of the extension tube. The side door choke 46 and the plug choke 44 are then removed in that order and an extension tube 63 is posi-

tioned, as shown in FIGURE 3, with its lower end in the passage 28, by means of an extension hanger 64 which has means engaging in the landing recess 34 to hold it in position. The lower end of the extension tube 63 is provided with a packer or sealing means 65 which seals between the internal wall of the passage 28 and the exterior of the extension tube, while the extension hanger 64 is provided with packers or sealing means 66 and 69, which prevent flow between the extension hanger and the tubing string and also through the side ports 39.

It will now be seen that chemicals or other fluids may be circulated downwardly through either tubing string, for example, the tubing string 24, through the extension hanger 64, extension tube 63 and passage 28 of the twin nipple, to the lower producing zone, and from there upwardly through the extension tube 60 and the tubing string 25 back to the surface. Of course, the fluids may be circulated in the opposite direction, if desired.

When it is desired to work over the upper producing zone, the extension tubes 60 and 63 are removed, and plug chokes 70 and 71 are lowered into and positioned in the passages 29 and 28, respectively. The plug chokes are provided with sealing means 72 and 73, whereby flow of fluid is prevented through the passages of the twin nipple.

A side door choke 74, identical to choke 46, is then disposed in the tubing string 24, and finally an extension tube 75 is positioned, as shown in FIGURE 4, in the tubing string 25 by means of an extension hanger 76, said extension tube having its lower end disposed just above the plug choke 70.

Fluid for working over the upper producing zone 22 may then be circulated down through the tubing string 24, the passage 77 of the side door choke 74 into the casing above the twin nipple, and then back to the surface through the extension tube 75 and the tubing string 25. If it becomes desirable to wash off the upper surfaces of the twin nipple and the plug chokes 70 and 71 after treatment of the upper zone is completed, the washing fluid is circulated in the direction opposite to that of the treating fluid, whereby the washing fluid flows downwardly out of the lower end of the extension tube 75 immediately above the plug chokes 70 and 71, and then flows upwardly over said chokes to wash sand or other extraneous matter off the upper ends of said chokes and the twin nipple. Treating fluids are likewise washed out in this manner.

It will now be seen that the method of completing and working over wells having two producing zones includes providing two tubing strings whose lower ends are positioned above the upper producing zone, disposing between the two producing zones a nipple which has a pair of passages providing communication between the two zones, said nipple having means for selectively directing well tools to either of the two passages, closing one of the passages by means of a plug means, and connecting the other passage to one of the tubing strings by means of an extension tube 40 to complete the well and provide for simultaneous flow of well fluids from the two producing zones to the surface through the two tubing strings, connecting one of the passages of the nipple to one of the tubing strings 24 by means of one extension tube 63, and extending another extension tube from the other of the tubing strings through the other of the nipple passages to work over the lower zone, and closing the passages by means of plug chokes, and extending an extension tube downwardly from one of the tubing strings to work over the upper zone.

It will also be noted that the method herein described provides no permanent non-removable connection between the lower producing zone and a tubing string which extends to the surface, whereby working over the upper zone is easily accomplished by blocking or plugging off the lower zone from the upper zone by means of the plug chokes 70 and 71.

Referring now particularly to FIGURES 5 and 6 of the drawings, one specific embodiment of twin nipple or housing member 80 is shown to be of cylindrical form having an internal wall 81 which provides the housing member or nipple with a small eccentrically disposed longitudinal passage 82 and a large longitudinal passage 83, also eccentrically disposed. A plug choke 84 is disposed in the smaller passage and an extension tube hanger 85 is disposed in the larger passage. A sleeve 86 has its upper end telescoped in the lower enlarged end of the larger passage 83 and is held in place in longitudinal alignment therewith so as to form a continuation of said larger passage by a spacer or positioning ring 87 and a locking ring 88 which is threaded in the lower end of the twin nipple 80. The spacer ring 87 has an eccentric bore 89a which receives the reduced lower end of the sleeve 86 and provides an annular upwardly facing shoulder 90 on which the downwardly facing annular shoulder 91 of the sleeve rests. The ring 88 is locked in place by a set screw 92 so that a second eccentric bore 89b in the ring 87 is aligned with the small passage 82 of the nipple. The upper end of the sleeve 86 is provided with a seal ring 94 which seals between the sleeve and the nipple.

The upper end of the internal wall 81 of the nipple is beveled to provide an inclined ramp 96 which extends and inclines downwardly from above the smaller passage 82 toward the larger passage 83, and a second inclined ramp 97 extends and inclines downwardly, in a direction opposite to the ramp 96, from the larger passage 83 toward the smaller passage 82. The upper surface 98a of the nipple is inclined inwardly and downwardly toward the upper end of the upper ramp 96 to guide well tools thereto.

The upper ramp is of such size that the lower end of a large diameter well tool, such as the extension hanger 85, will be caused to be moved toward the large passage 83 when it is lowered into the nipple 80. The smaller well tool or plug choke 84 is then lowered into the nipple and, since the larger passage 83 is now occupied by the larger well tool 85, the smaller tool 84 upon entering the nipple cannot enter the larger passage and is directed and guided toward the smaller passage 82 by the lower or second ramp 97.

The nipple 80 is internally threaded at its lower end, as at 98, whereby a packer mandrel 99 may be secured to such lower end of the nipple, the packer (not shown) sealing between the nipple and the casing in which it is disposed. A set screw 100 locks the packer mandrel to the nipple.

The plug choke 84 is provided with a suitable locking means, such as the dogs or slips 105 which are adapted to enter an internal annular locking recess 101 in the passage 82 to lock the plug choke in place in such smaller passage. The slips are held in expanded positions by the frusto-conical locking surface 102 of the body or mandrel 103 of the choke. The upper reduced portion of the choke mandrel has a slip carrier 104 slidable thereon which carries the slips or dogs 105. The upper end of the mandrel extends above the slip carrier whereby the plug choke can be removed from the smaller passage by a suitable retrieving tool which first engages the upper end of the main body or mandrel 103 of the plug choke to drive it downwardly whereby the slips are freed to move to retracted position, and then engages the undercut flange 107 at the upper end of the slip carrier, whereupon the retrieving tool may be raised to pull the plug choke upwardly out of the nipple. A packer assembly or sealing means 106 on the plug choke seals between the plug choke mandrel and the nipple to prevent flow of fluid through the smaller passage 82 when the plug choke is disposed therein. A boss or head 103 on the extreme lower end of the choke mandrel serves to guide the plug choke into the passage and is adapted to engage the upper surface of the positioning ring 87

surrounding the bore 89b to limit downward movement of the plug choke in said passage and to position the slips 105 for expansion to engagement in the locking recess 101 in such passage.

The extension hanger 85 shown in the large passage includes a main mandrel 110 having a key carrier sleeve 111 mounted on its reduced lower end portion by means of a sub 112 threaded on the lower end of said mandrel. The key carrier sleeve is threaded onto the upper end of the sub, and the upper end of the sleeve retains a packing or sealing assembly 123 in place on said main mandrel between the upper end of said sleeve and a downwardly facing shoulder 124 on the mandrel. The sealing assembly seals between the main mandrel and the bore wall of the large passage to prevent flow of fluids therebetween. Selector stop keys 113 are carried within the carrier sleeve 111, and said keys each have a pair of bosses 114a and 114b which project through openings 115 on opposite sides of the carrier sleeve. A spring 116 surrounds the main mandrel and engages the keys to bias the keys apart so that the bosses are biased toward expanded position. The selector key bosses are adapted to engage in complementarily shaped recesses 117a and 117b formed in the bore wall of the sleeve 86, such engagement limiting downward movement of the extension hanger in the large passage.

Locking dogs 118 are supported by a dog carrier sleeve 119 slidably mounted on an elongate neck member 120 threaded into the upper end of the main mandrel and forming an upward extension thereof. The bosses 118a on the lower ends of the dogs are expanded into expanded locking position in a locking recess 121 formed in the bore wall of the sleeve 86 by the frusto-conical expander surface 122 formed on the upper end portion of the main mandrel. Such engagement of the dog bosses in the locking recess prevents upward displacement of the extension hanger.

As shown, the extension hanger also has a plug member 125 fitting into the bore of the neck member extension 120 of the main mandrel and held in place therein by a shear pin 126. A sealing ring 127 carried by the plug member seals between said plug member and the neck member to prevent flow of fluids through the bore of the extension hanger. The plug member may be removed from its plugging position by means of a suitable retrieving tool engaging over the undercut annular flange 128 at the upper end of the plug member, and pulling upwardly thereon to shear the pin 126.

The extension hanger may be removed from its position in the sleeve 86 by means of a suitable retrieving tool (not shown) which first moves the main mandrel downwardly until the engagement of the selector keys in the recesses 117a and 117b prevents further downward movement. The retrieving tool then engages the undercut annular flange 130 at the upper end of the dog carrier sleeve 119, and an upward pull lifts the dog carrier sleeve and the locking dogs 118 carried thereby. Such upward movement of the locking dogs moves their lower ends upwardly along the frusto-conical expander surface and out of the locking recess 121, whereupon the extension hanger may be lifted out of the large passage in the sleeve 86, and then upwardly out of the flow conductor.

A coupling or guide nut 132 is shown threaded on the lower end of the sub 112 of the extension hanger, and it will be apparent that an extension tube or any other suitable tool could be connected thereto or substituted therefor.

A plug choke and an extension hanger have been described as situated in the passages of the twin nipple merely for purposes of illustrating how well tools may be removably positioned in the passages of the twin nipple, it being obvious from the foregoing description of the method of completing and working over a well that different tools are removably positioned in the passages of

the twin nipple during different operations or steps of the method.

Referring now to FIGURES 7 and 8, a housing member or nipple 140 is shown having three differently sized passages, 141, 142 and 143, and having large ramps 144 for engaging and guiding a large tool 145 into the largest passage 141, a smaller ramp 146 for guiding a smaller tool 147 into the middle-sized passage 142, and a smallest ramp 148 for guiding the smallest tool 149 into the smallest passage 143. The upper surface 140a of the nipple is inclined at all points inwardly and downwardly toward the upper end of the large ramp 144, so that any tool engaging it is guided thereby toward the large ramp first. The tools, of course, are lowered in order of their size, the largest 145 being moved into its passage 141 first, and the next largest 147 being moved into its passage 142 before the smallest 149 is moved into its passage 143, so that the smaller tools are prevented from entering into the larger passages of the nipple since these passages are already blocked by or filled with tools.

In FIGURE 11 is illustrated another housing member or nipple 150 having a pair of large passages 151 and a pair of small passages 152. Primary large ramps 153 are inclined downwardly and inwardly toward a pair of downwardly and outwardly inclined secondary large ramps 154 which lead toward the larger passages 151 to guide large tools to either of said large passages. After these large tools have been positioned in the large passages 151, the smaller secondary ramps 155, which incline downwardly and outwardly toward the smaller passages 152, guide smaller tools into the smaller passages. The top surface of the nipple is inclined toward the primary ramps 153 at all points to guide tools toward the primary ramps 153 as they are lowered into the nipple.

FIGURE 9 illustrates a nipple or housing member 160 having a pair of large passages 161 and a small passage 162. Large primary ramps 163 and 164 are inclined toward the large passages 161 to guide large tools thereto, while a small secondary ramp 165 is inclined toward the small passage 162 to guide a small tool thereinto after large tools have been positioned in the large passages 161. The upper surface of the nipple 160 is inclined toward the upper end of the primary ramp 163 to guide tools toward the primary ramp as they are lowered into the nipple.

In FIGURE 10 is illustrated another nipple or housing member 170 having three passages 171, 172 and 173 of progressively smaller size and provided with arcuate large primary ramp 174 which inclines arcuately downwardly toward the largest passage, a smaller ramp 176 which inclines downwardly back toward the smaller passage 172 and a smallest ramp 177 which inclines further downwardly toward the smallest passage 173. The top surface 178 of the nipple inclines toward the upper end of the largest ramp, whereby tools lowered into the nipple are guided thereby toward the largest ramp.

In many cases an extension tube and hanger, such as that illustrated at 40 and 41 in FIGURE 2, is preferably positioned in one string of well tubing with its lower end engaged in the larger passage of the nipple 20 before any well tool is introduced through the other tubing string to be positioned in the smaller passage of the nipple. This arrangement facilitates the entry of the smaller tool into the smaller passage of the nipple, though it is not essential to successful operation of the device.

It will now be seen that nipples or housing members of different configurations have been illustrated and described, each of which has a plurality of passages and is provided with large primary ramps or inclined surfaces which guide a large tool toward a large passage and secondary ramps or inclined surfaces which guide smaller tools to smaller passages. It will also be seen that the top surfaces of the nipples are inclined toward the upper ends of the primary ramps upon engaging the upper surface of the nipple. It will also be seen that tools are positioned in the passages of the nipples in accordance

with the sizes thereof, tools being positioned first in the largest passage of each nipple and then in the progressively smaller passages.

The foregoing description of the invention is explanatory only, and changes in the details of the construction illustrated may be made by those skilled in the art, within the scope of the appended claims, without departing from the spirit of the invention.

What is claimed and desired to be secured by Letters Patent is:

1. The method of completing a well having two producing zones, including: disposing a pair of tubing strings in a well, such tubing strings having lower ends disposed above the upper producing zone; disposing a nipple between the two producing zones, said nipple having a pair of passages providing communication between the two zones and also having means thereon selectively determining entry of well tools into said passages; selectively closing a predetermined selected one of the two passages; and establishing a flow course selectively connecting the other passage to a selected one of either of the two tubing strings without moving the tubing strings in place in the well, whereby fluid from the lower zone may flow to the surface through the said other passage and said one of the tubing strings to the surface, and fluid from the upper zone may flow through the other tubing string to the surface.

2. The method of completing a well having two producing zones, including: disposing a pair of tubing strings in a well, said tubing strings having lower ends disposed above the upper producing zone; disposing a nipple between the two producing zones, said nipple having a pair of passages providing communication between the two zones also having means thereon selectively determining entry of well tools into said passages; selectively closing a predetermined selected one of the two passages; and establishing a flow course selectively connecting the other passage to a selected one of either of the two tubing strings without moving the tubing strings in place in the well, whereby fluid from the lower zone may flow to the surface through the said other passage and said one of the tubing strings to the surface and fluid from the upper zone may flow through the other tubing string to the surface; and working over the lower zone by establishing a flow course selectively connecting a selected desired one of either of the tubing strings to a selected desired one of the passages and removably disposing an extension tube from the other tubing string through the other passage and below the nipple in sealing engagement with both said other tubing string and said other passage of said nipple to provide a flow conduit therebetween, whereby fluids may be circulated through the tubing strings and the lower zone.

3. A producing and servicing apparatus for a well having two producing zones and including: a casing; a pair of tubing strings within the casing extending from the surface of the well to a point above the producing zones; means sealing between the lower end portions of the tubing strings and the casing above the producing zones, said tubing strings having means engageable with well tools for positioning and releasably holding said tools in the tubing strings; a nipple disposed in the well casing below the lower end of the tubing strings between the two zones; and means sealing between the nipple and the casing, said nipple having partition means providing a plurality of passages extending longitudinally through said nipple and affording communication between the two zones, said nipple having means in each of said passages engageable with well tools for positioning and releasably holding said tools in said passages; one of said passages being larger than the others, said nipple having inclined ramps at the upper ends of said partition means for selectively guiding tools of different sizes to said passages; said nipple passages being sized to receive well tools

passed downwardly through said tubing strings to engage said nipple.

4. A producing and servicing apparatus for a well having two producing zones and including: a casing; a pair of tubing strings within the casing extending from the surface of the well to a point above the producing zones; means sealing between the lower portion of the tubing strings and the casing above the two producing zones, said tubing strings having means engageable with well tools for positioning and releasably holding said tools in the tubing strings; a nipple disposed in the well casing between the two zones; and means sealing between the nipple and the casing, said nipple having partition means providing a plurality of passages affording communication between the two zones, said passages being adapted to receive well tools passed downwardly through said tubing strings to said nipple, said nipple having means in said passages engageable with well tools for positioning and releasably holding said tools in said passages; said nipple having an upper surface provided with guide means thereon for selectively guiding well tools toward the upper ends of said partition means defining said passages to guide well tools to selected ones of said passages.

5. A means for producing and servicing a well having two producing zones and including: a casing; a pair of tubing strings within the casing extending from the surface of the well to a point above the producing zones; means sealing between the lower portions of the tubing strings and the casing, said tubing strings having means engageable with well tools for positioning and releasably holding said tools in the tubing strings; a nipple disposed in the well casing between the two zones; and means sealing between the nipple and the casing, said nipple having partition means providing a plurality of passages affording communication between the two zones, said passages being adapted to receive well tools passed downwardly through said tubing strings to said nipple, said nipple having means in said passages engageable with well tools for positioning and releasably holding said tools in said passages; one of said passages being larger than the others, said nipple having inclined ramps at the upper ends of said partition means engageable by well tools for selectively guiding tools of different sizes to said passages; said nipple having an upper surface inclined toward said ramps to guide tools thereto.

6. A well device including: a nipple having internal partition means forming a plurality of passages extending longitudinally of said nipple; means in each of said passages engageable with insertable and removable well tools and cooperating therewith to releasably position and hold the tools in the passages, said passages being of different diameters, said nipple having means forming an inclined primary ramp at its upper end for guiding tools to the largest passage and second means providing an inclined secondary ramp below said primary ramp for guiding tools toward the smaller passages.

7. A nipple having partition means providing a pair of separate laterally spaced longitudinally extending passages and landing and locking recesses in each of said passages engageable with removable well tools and cooperative therewith to position and releasably hold tools in the passages, said nipple having inclined surfaces at the upper ends of the partition means providing a pair of inclined ramps for guiding tools toward the upper ends of said passages, one of said passages being larger than the other, one of said ramps being a primary ramp for guiding large tools toward the upper end of the large passage and the other of said ramps being a secondary ramp for guiding smaller tools toward the upper end of the smaller passage.

8. A nipple adapted to be connected in a well flow string and having internal partition means forming a first passage therein and a second passage therein spaced from said first passage and disposed eccentrically of the longitudinal axis of said nipple, said second passage having

means therein for landing and locking engagement with a removable well tool, guide means in said nipple inclined from the upper end of said nipple to the upper end of said first passage adapted to guide a well tool into said first passage, and a downwardly inclined guide surface at the upper end of the nipple extending downwardly to said second passage from said guide means and said first passage for directing a well tool engaging said surface to said second passage.

10. A producing and servicing apparatus for a well having two producing zones and including: a casing; a pair of tubing strings within the casing extending from the surface of the well to a point above the producing zones; said tubing strings having means connected therein engageable with well tools for positioning and releasably holding said tools in the tubing strings; and a nipple disposed in the well casing spaced below the lower end of the tubing strings and between the two zones and having means sealing between the nipple and the casing, said nipple having partition means providing a plurality of separate laterally spaced longitudinally extending passages affording communication between the two zones, said nipple having inclined guide means at the upper end of the partition means and inclined guide ramps for selectively directing well tools from said guide means into selected ones of each of said passages, said passages each having means therein engageable with well tools for positioning and releasably holding said tools in said passages.

11. A producing and servicing apparatus for a well having two producing zones and including: a casing; a pair of tubing strings within the casing extending from the surface of the well to a point above the producing zones; said tubing strings having means therein engageable with well tools for positioning and releasably holding said tools in the tubing strings; a nipple disposed in the well casing spaced below the lower ends of the tubing strings and between the two zones; and means sealing between the nipple and the casing, said nipple having partition means providing a plurality of separate laterally spaced longitudinally extending passages affording communication between the two zones, said passages each having means engageable with well tools for positioning and releasably holding said tools in said passages; said nipple having an upper surface inclined downwardly and inwardly toward said passages, and a plurality of guide ramps extending to said passages from said guide means and engageable by well tools to guide said well tools selectively to selected ones of said passages.

11. A producing and servicing apparatus for a well having two producing zones and including: a casing; a pair of tubing strings within the casing extending from the surface of the well to a point above the producing zones, said tubing strings each having means therein engageable with well tools for positioning and releasably holding said tools in said tubing strings; a nipple disposed in the well casing between the two producing zones and spaced below the lower ends of said tubing strings; means sealing between the nipple and the casing; said nipple having internal partition means providing a plurality of separate laterally spaced longitudinally extending passages therethrough providing communication between the two zones, said nipple having means thereon and in said passages engageable with well tools for selectively positioning and releasably holding said well tools in said passages; and an extension tube having a well tool at its upper end engageable in the means in one of said tubing strings for holding said tool in said tubing string, said tube extending downwardly from said tubing string into a selected one of the passages of said nipple, said tube having means at its lower end selectively engaging said selected one of said passages of said nipple, said tube also having means sealing between said tube and said nipple, whereby well fluid from below said nipple is directed through said tube to said one of said tubing strings and thence to the sur-

face of the well, and removable plug means releasably disposed in each of the other passages of the nipple.

12. A well device including: a nipple having internal partition means forming a plurality of separate longitudinally extending passages providing flow courses therethrough; inclined ramps at the upper ends of said partition means for selectively guiding well tools toward selected ones of said passages; and an inclined upper surface at the upper end of said nipple for guiding well tools toward said ramps.

13. A well producing and servicing apparatus for a well having two producing zones and including: a casing; a pair of tubing strings within the casing extending from the surface of the well to a point above the producing zones; means sealing between the tubing strings and the casing, said tubing strings having means engageable with well tools for positioning and releasably holding said tools in the tubing strings; a nipple disposed in the well casing below the lower end of the tubing strings and between the two zones; means sealing between the nipple and the casing, said nipple having partition means providing a plurality of passages extending longitudinally therethrough affording communication between the two zones, said nipple having means thereon and in said passages engageable with well tools for selectively positioning and releasably holding said tools in selected ones of said passages; and an elongate well tool engaged at its upper end portion with the positioning and holding means of one of said tubing strings in sealing connection therewith and having means on its lower portion engageable with said means on said nipple for selectively positioning the same with its lower portion extending within and in sealing engagement with a selected one of the passages of said nipple.

14. A producing and servicing apparatus for a well having two producing zones and including: a casing; a pair of tubing strings within the casing extending from the surface of the well to a point above the producing zones; means sealing between the tubing strings and the casing near the lower ends of said tubing strings and above the producing zones, said tubing strings having means engageable with well tools for positioning and releasably holding said tools in the tubing strings; a nipple disposed in the well casing below the lower ends of the tubing strings and between the two zones; means sealing between the nipple and the casing, said nipple having partition means providing a plurality of passages extending longitudinally therethrough affording communication between the two zones, said nipple having means in each of said passages engageable with well tools for positioning and releasably holding said tools in said passages; said nipple having inclined selective ramps at the upper ends of said partition means for guiding tools to said passages and an upper guide surface for guiding tools to said ramps; and a well tool having means on its upper portion engaged with the positioning and holding means of one of said tubing strings and having lower means engaged with a selected one of the passages of said nipple, said well tool having means on its lower end engageable with the inclined ramps of said nipple for guiding said well tool into said selected passage.

15. A well device including: a nipple having partition means providing a plurality of separate laterally spaced longitudinally extending passages; means in each of said passages in said nipple engageable with well tools insertable into said passages and removable therefrom and cooperating therewith to releasably position and hold the tools in the passages, said nipple having inclined surfaces at the upper ends of said partition means providing an upper guide surface extending downwardly and inwardly to a plurality of inclined guide ramps each selectively inclined toward one of the passages of said nipple for selectively guiding well tools toward selected ones of said passages.

16. A well device including: a nipple having partition means providing a plurality of separate laterally spaced

longitudinally extending passages; means in each of said passages in said nipple engageable with well tools releasably positioned in said passages and removable therefrom, said means cooperating with said well tools to releasably position and hold the tools in the passages, said nipple having inclined surfaces at the upper ends of said partition means providing inclined ramps each inclined toward a selected one of said passages for selectively guiding tools toward selected ones of the passages, said nipple having an inclined upper surface for guiding tools toward said ramps.

17. A device of the type described, including a nipple having internal partition means forming a plurality of separate laterally spaced longitudinally extending passages; means in each of said passages engageable with well tools insertable into and removable from said passages, said means cooperating with said well tools to releasably position and hold the tools in the passages, said passages being of different diameters, said nipple having means providing an inclined primary ramp for guiding tools to the upper end of the largest passage and second means providing an inclined secondary ramp for guiding tools toward the upper ends of the smaller passages, said nipple having an upper surface inclined toward the upper end of the inclined primary ramp for guiding tools thereto.

18. A nipple adapted to be positioned in a well bore and having partition means therein providing a plurality of separate laterally spaced longitudinally extending passages, each of said passages having therein landing and locking recesses engageable with removable well tools and cooperative therewith to position and releasably hold tools in the passages, said nipple having inclined surfaces at the upper ends of said partition means providing separate inclined ramps each inclined toward one of said passages for selectively guiding tools toward the upper ends of selected ones of said passages, said nipple having an upper surface inclined toward the upper ends of said inclined surfaces providing said ramps for guiding tools thereto.

19. A nipple having partition means providing a pair of separate laterally spaced longitudinally extending passages and landing and locking recesses in each of said passages engageable with removable well tools and cooperative therewith to position and releasably hold tools in the passages, said nipple having an inclined surface at its upper end for guiding tools toward the upper ends of said passages, one of said passages being larger than the other; a first inclined surface at the upper end of said partition means providing a primary ramp for guiding large tools toward the upper end of the large passage and a second inclined surface in said nipple at the upper end of said partition means below said first inclined surface providing a secondary ramp for guiding smaller tools toward the upper end of the smaller passages, said nipple having an upper surface inclined downwardly and inwardly toward the upper end of the primary ramp to guide tools thereto.

20. Apparatus for producing a cased bore hole penetrating a plurality of spaced apart hydrocarbon productive intervals comprising two parallel, eccentric, coextensive, spaced apart tubing strings arranged in said bore hole, the lower open ends of said tubing strings being positioned above the uppermost of said productive intervals first packing means positioned on said tubing strings adjacent the lower ends thereof adapted to seal off the space between said tubing strings and said casing, second packing means provided with two spaced apart bores therethrough positioned in said bore hole between said uppermost productive interval and said lower productive interval and adapted to seal off the space between the walls of said bores and said casing, guide means on the upper end of said second packing means, a plug having means thereon for selectively engaging in one of said bores, said plug being adapted to prevent fluid flow

through said bore, and a tubing extension sealingly supported in one of said tubing strings and having means thereon engageable with said guide means of said second packing means and coacting with said other bore for directing the lower end thereof selectively through said other bore, said tubing extension having means thereon sealingly engaging with the wall of said other bore and being open ended whereby production fluids from said lower interval are isolated from production fluids from said upper interval, said fluids from said lower interval flowing upwardly through said tubing extension and through said one tubing string and fluids from said upper interval flowing upwardly through said other tubing string.

21. In subsurface well production apparatus adapted for use with first, second and third tubular strings extending to the top of a well bore; a head adapted to be disposed in the well bore and having first, second and third passages therein; said head having means in said first passage for receiving the first tubular string which extends to the top of the well bore; said head having an upper tapered surface through which said passages open, said second passage having a greater entrance diameter than said third passage, whereby engagement of said tapered surface by the second tubular string extending to the top of the well bore will direct the second tubular string into said second passage and engagement of said tapered surface by the third tubular string extending to the top of the well bore will direct the third tubular string into said third passage.

22. In subsurface well production apparatus adapted for use with first, second and third tubular strings extending to the top of a well bore; a head adapted to be disposed in the well bore and having first, second and third passages therein; said head having means in said first passage for receiving the first tubular string which extends to the top of the well bore; said head having an upper tapered surface through which said passages open, said second passage having a greater entrance diameter than said third passage and said third passage opening through said tapered surface at a higher elevation than said second passage opens through said tapered surface, whereby engagement of said tapered surface by the second tubular string extending to the top of the well bore will direct the second tubular string into said second passage and engagement of said tapered surface by the third tubular string extending to the top of the well bore will direct the third tubular string into said third passage.

23. In subsurface well production apparatus designed for use with a plurality of tubing strings extending to the top of the well bore; a head adapted to be disposed in the well bore and having a plurality of separate longitudinal passages therein, said head having an upper tapered surface through which said passages open, said head having means in said first passage for receiving one of said tubing strings which extends to the top of the well bore; said other passages than said first passages each having an entrance diameter different from each other and different from said first passage, whereby engagement of said tapered surface by a plurality of successive tubing strings extending to the top of the well will direct said tubing strings successively into selected ones of said passages determined by the size of said passages and said tubing strings.

24. In subsurface well production apparatus designed for use with a plurality of tubing strings extending to the top of the well bore; a head adapted to be disposed in the well bore and having a plurality of separate longitudinal passages therein, said head having an upper tapered surface through which said passages open, said head having means in said first passage for receiving one of said tubing strings which extends to the top of the well bore; said other passages than said first pas-

sage having entrance diameters differing progressively from the diameter of said first passage, whereby engagement of said tapered surface by a plurality of successive tubing strings extending to the top of the well and having progressively differing diameters at their lower ends will direct said tubing strings successively into selected ones of said passages determined by the size of said passages and said tubing strings.

25. In subsurface well production apparatus adapted for use with a plurality of tubing strings extending to the top of the well bore; a head adapted to be disposed in the well bore and having first, second and third passages therein, one of said tubing strings having means connected therewith extendable into said first passage in sealing relation therewith; a second of said strings having means connected therewith for extending downwardly into said second passage of said head, said third passage of said head being adapted to receive another well device; said head having an upper tapered surface through which said passages open, said second passage having a greater entrance diameter than said first passage, and said third passage opening through said tapered surface having a greater entrance diameter than said second passage, whereby engagement of said tapered surface by said tubular strings extending to the top of the well bore will direct said tubular strings into the one of said passages corresponding in size thereto, and engagement of said tapered surface by said other well device will direct said other well device into said third passage.

26. In subsurface well production apparatus adapted for use with first, second and third tubular strings extending to the top of a well bore; a head adapted to be disposed in the well bore and having first, second and third passages therein; said head having means in said first passage for receiving the first tubular string which extends to the top of the well bore; first guide means on said head adapted to be engaged by the second tubular string which extends to the top of the well bore to direct the second tubular string into said second passage; and second guide means on said head separate from said first guide means and extending from said third passage to a position closely adjacent to one of said other passages, said second guide means being adapted to be engaged by the third tubular string which extends to the top of the well bore to direct the third tubular string from the position closely adjacent to said one of said other passages into said third passage.

27. In subsurface well production apparatus adapted for use with first, second and third tubular strings extending to the top of a well bore; a head adapted to be disposed in the well bore and having first, second and third passages therein; said head having means in said first passage for receiving the first tubular string which extends to the top of the well bore; and guide means on said head adapted to be engaged by the second and third tubular strings to direct the second and third tubular strings into said second and third passages, respectively, said guide means including a surface tapering downwardly from a position closely adjacent to said third passage to said second passage to direct the second tubular string from a position closely adjacent to said third passage to said second passage and another surface offset from and tapering downwardly from a position closely adjacent to said second passage to said third passage to direct the third tubular string from a position closely adjacent to said second passage to said third passage.

28. In apparatus to be disposed in a well bore; a body member having first and second passages therein, said first passage having a larger diameter than said second passage; first guide means on said body inclined downwardly toward and extending to said second passage and adapted to be engaged by a second tubular string extending from the top of the well bore to direct said second tubular string to said second passage; and a second guide

means on said body inclined downwardly from said second passage toward and extending to said first passage and adapted to be engaged by a first tubular string extending to the top of the well bore to direct said first tubular string to said first passage.

29. In apparatus to be disposed in a well bore: a body member having first and second passages therein, said first passage having a larger diameter than said second passage; first guide means on said body inclined downwardly toward and extending to said second passage; a second tubular string extending to the top of the well bore and engageable with said first guide means to be directed thereby toward said second passage; a second guide means on said body inclined downwardly from said second passage toward and extending to said first passage; and a first tubular string extending to the top of the well bore and engageable with said second guide means to be directed thereby toward said first passage, said first tubular string having a larger diameter than said second passage and adapted to move into said first passage.

30. In subsurface well production apparatus adapted for use with first, second and third tubular strings extending to the top of a well bore: a head adapted to be disposed in the well bore and having first, second and third passages therein; said head having means in said first passage for receiving the first tubular string which extends to the top of the well bore; said head having an upper inwardly and downwardly inclined surface through which said passages open, said second passage having a greater entrance diameter than said third passage, whereby engagement of said inwardly and downwardly inclined surface by the second tubular string extending to the top of the well bore will direct the second tubular string into said second passage and engagement of said inclined surface by the third tubular string extending to the top of the well bore will direct the third tubular string into said third passage.

31. In a well having a plurality of formation zones and a casing therein: production apparatus in the casing comprising first, second and third tubular strings extending to the top of the well bore, a head having first, second and third passages into which said first, second and third strings, respectively, are insertable, said head having an upper tapered surface through which said passages open, said first passage having a greater entrance diameter than said second passage, said second passage having a greater entrance diameter than said third passage, said first tubular string having a greater diameter than said second passage, whereby engagement of said first tubular string with said tapered surface will direct said first tubing string past said third passage and said second passage into said first passage, said second string having a greater diameter than said third passage, whereby engagement of said tapered surface by said second tubular string will direct said second tubular string past said third passage into said second passage and engagement of said tapered surface by said third tubular string will direct said third tubular string into said third passage.

32. In a well having a plurality of formation zones and a casing therein: production apparatus in the casing comprising first, second and third tubular strings extending to the top of the well bore, a head having first, second and third passages into which said first, second and third string, respectively, are insertable, said head having an inwardly and downwardly inclined surface through which said passages open, said second passage having a greater entrance diameter than said third passage, said second string having a greater diameter than said third passage, whereby engagement of said inwardly and downwardly inclined surface by said second tubular string will direct said second tubular string past said third passage into said second passage and engagement of said inclined surface by said third string will direct said third string into said third passage.

33. In subsurface well production apparatus adapted for use with first, second and third tubular strings extending to the top of a well bore; a head adapted to be disposed in the well bore and having first, second and third passages therein; said head having means in said first passage for receiving the first tubing string which extends to the top of the well bore; first guide means on said head adapted to be engaged by the second tubular string which extends to the top of the well bore to direct the second tubular string into said second passage; and second guide means on said head separate from said first guide means and adapted to be engaged by the third tubular string which extends to the top of the well bore to direct the third tubular string into said third passage; wherein said first guide means comprises a first ramp on said head inclined downwardly toward said second passage and engageable by the second tubular string which extends to the top of the well bore to direct the second tubular string into said second passage; and said second guide means comprises a second ramp on said head separate from said first ramp and inclined downwardly from said second passage toward said third passage and engageable at a location of close adjacency to said second passage, by the third tubular string which extends to the top of the well bore to direct the third tubular string into said third passage.

34. In subsurface well production apparatus adapted for use with first, second and third tubular strings extending to the top of the well bore: a head adapted to be disposed in the well bore and having first, second and third passages therein; said head having means in said first passage for receiving the first tubing string which extends to the top of the well bore; first guide means on said head adapted to be engaged by the second tubular string which extends to the top of the well bore to direct the second tubular string into said second passage; and second guide means on said head separate from said first guide means and adapted to be engaged by the third tubular string which extends to the top of the well bore to direct the third tubular string into said third passage; wherein said first guide means comprises a first ramp on said head curved arcuately and inclined downwardly from a point remote from said second passage to a low point adjacent said second passage, said first ramp being engageable by the second tubular string which extends to the top of the well bore to direct the second tubular string into said second passage, and said second guide means comprises a second ramp on said head curved arcuately and inclined downwardly from a high point remote from said third passage to a low point adjacent said third passage, said second ramp being engageable by the third tubular string which extends to the top of the well bore to direct the third tubular string into said third passage.

35. In subsurface well production apparatus adapted for use with first, second and third tubular strings extending to the top of a well bore: a head adapted to be disposed in the well bore and having first, second and third passages therein; said head having means in said first passage for receiving the first tubing string which extends to the top of the well bore; first guide means on said head adapted to be engaged by the second tubular string which extends to the top of the well bore to direct the second tubular string into said second passage; and second guide means on said head separate from said first guide means and adapted to be engaged by the third tubular string which extends to the top of the well bore to direct the third tubular string into said third passage; wherein said first guide means comprises a first ramp surface on said head curved arcuately and inclined downwardly from a high point to a low point adjacent said second passage, said first ramp surface being engageable by the second tubular string which extends to the top of the well bore to direct the second tubular string into said second passage, and said second

guide means comprises a second ramp surface on said head curved arcuately and inclined downwardly from a high point to a low point adjacent said third passage, said second ramp surface being engageable by the third tubular string which extends to the top of the well bore to direct the third tubular string into said third passage.

36. In subsurface well production apparatus adapted for use with first, second, and third tubular strings extending to the top of a well bore: a head adapted to be disposed in the well bore and having first, second and third passages therein; said head having means in said first passage for receiving the first tubing string which extends to the top of the well bore; first guide means on said head adapted to be engaged by the second tubular string which extends to the top of the well bore to direct the second tubular string into said second passage; and second guide means on said head separate from said first guide means and adapted to be engaged by the third tubular string which extends to the top of the well bore to direct the third tubular string into said third passage; wherein said first guide means comprises a guide surface on said head curved arcuately and inclined downwardly from a high point remote from said second passage to a low point adjacent said second passage, said first guide surface being engageable by the second tubular string which extends to the top of the well bore to direct the second tubular string into said second passage, and said second guide means comprises a second guide surface on said head curved arcuately and inclined downwardly from a high point adjacent said second passage to a low point adjacent said third passage, said second guide surface being engageable by the third tubular string which extends to the top of the well bore to direct the third tubular string into said third passage.

37. In subsurface well production apparatus adapted for use with first, second and third tubular strings extending to the top of a well bore; a head adapted to be disposed within the well bore and having first, second and third passages therein; said head having first means in said first passage for receiving the first tubular string which extends to the top of the well bore; said head having second means in said second passage for receiving the second tubular string which extends to the top of the well bore; said head having third means in said third passage for receiving the third tubular string which extends to the top of the well bore; and a guide surface curved arcuately with respect to the axis of the head and integral with said head, said guide surface having an upper end inclined in a downward direction toward said third passage and adapted to be engaged by the third string to conduct the third string into said third means.

38. In subsurface well production apparatus adapted for use with first, second and third tubular strings extending to the top of a well bore; a head adapted to be disposed within the well bore and having first, second and third passages therein; said head having first means in said first passage for receiving the first tubular string which extends to the top of the well bore; said head having second means in said second passage for receiving the second tubular string which extends to the top of the well bore; said head having third means in said third passage for receiving the third tubular string which extends to the top of the well bore; and a guide surface curved arcuately with respect to the axis of the head and extending arcuately from said second passage to said third passage, said guide surface having an upper end inclined in a downward direction from a location adjacent said second passage to a location adjacent said third passage and adapted to be engaged by said third string to direct the third string into said third means.

39. In subsurface well production apparatus adapted for use with first, second and third tubular strings extending to the top of a well bore: a head adapted to be disposed in the well bore and having first, second and third passages therein; said head having first means in

said first passage for receiving the first tubular string which extends to the top of the well bore; said head having second means in said second passage for receiving the second tubular string which extends to the top of the well bore; said head having third means in said third passage for receiving the third tubular string which extends to the top of the well bore; and a guide surface curved arcuately with respect to the axis of the head and extending arcuately from said second passage, past said first passage to said third passage, said guide surface having an upper end inclined in a downward direction from a location adjacent said second passage to a location adjacent said third passage and adapted to be engaged by the third string to direct the third string into said third means.

40. In apparatus to be disposed in a well bore: a body member having first and second passages therein, said first passage having a larger diameter than said second passage; said body having an upper generally downwardly and inwardly inclined surface inclined downwardly toward and extending to said second passage and adapted to be engaged by a second tubular string extending to the top of the well bore to direct said second tubular string to said second passage; said body having a transverse groove extending downwardly from said upper inclined surface and having a base inclined downwardly from said second passage toward and extending to said first passage, said base being engageable by a first tubular string extending to the top of the well bore to direct said first tubular string to said first passage.

41. In apparatus to be disposed in a well bore: a body member having first and second passages therein; said body having an upper generally tapered surface inclined downwardly toward and extending to said second passage and adapted to be engaged by a second tubular string extending to the top of the well bore to direct said second tubular string to said second passage; said body having a transverse groove extending downwardly from said tapered surface and having a base inclined downwardly from said second passage toward and extending to said first passage, said base being engageable by a first tubular string extending to the top of the well bore to direct said first tubular string to said first passage.

42. In apparatus to be disposed in a well bore: a body member having first and second passages therein, said first passage having a larger diameter than said second passage; said body having an upper inwardly and downwardly inclined surface inclined downwardly toward and extending to said second passage; a second tubular string extending to the top of the well bore and engageable with said upper inclined surface to be directed thereby toward said second passage; said body having a transverse groove extending downwardly from said upper inclined surface and having a base inclined downwardly from said second passage toward and extending to said first passage; and a first tubular string extending to the top of the well bore and engageable with said base to be directed thereby toward said first passage, said first tubular string having a larger diameter than said second passage and adapted to move into said first passage.

43. In apparatus to be disposed in a well bore: a body member having first and second passages therein, said first passage having a larger diameter than said second passage; first guide means on said body inclined downwardly toward and extending to said second passage; a second tubular string extending to the top of the well bore engageable with said first guide means to be directed thereby toward said second passage; second guide means on said body inclined downwardly from said second passage toward and extending to said first passage; a first tubular string extending to the top of the well bore and engageable with said second guide means to be directed thereby toward said first passage, said first tubing string having a larger diameter than said second passage and adapted to move into said first passage; and means in said first passage for releasably securing a well tool in said

19

first passage of said body member, when said first tubular string is in said first passage.
